UNITED STATES PATENT OFFICE.

JIM B. FULLER AND JAMES P. UPHAM, OF CLAREMONT, NEW HAMPSHIRE

IMPROVEMENT IN PREPARING SHORT-STAPLE FIBERS FROM HEMP, FLAX, &c.

Specification forming part of Letters Patent No. 43,015, dated June 7, 1864.

To all whom it may concern:

Be it known that we, JIM B. FULLER and JAMES P. UPHAM, both of Claremont, in the county of Sullivan and State of New Hampshire, have invented a new and useful method of preparing flax, hemp, and other similar substances for "cottonizing" or rendering applicable to manufacture into textile fabrics on short-staple machinery; and we do hereby declare the following to be a full, clear, and exact description of the same, reference being had to the accompanying drawing, making part of this specification, wherein we have represented a vertical section of an apparatus in and by which our method may be performed.

Heretofore in the preparation of flax, hemp, &c., for fibrous and textile purposes, the fibrous material has been boiled either with water or alkaline solutions both in open and closed vessels, and with or without pressure, but in order to cleanse the fiber from the gummy substances the material has been taken from the vessel in which it was boiled and the washing and cleansing has been done while out of the vessel in which the material was boiled.

This invention is based on the known fact that when flax, hemp, or other similar substances are boiled with water in a close vessel under a high temperature and pressure, the gummy and coloring matter contained in such substances is dissolved or softened so that it can be easily pressed out from the fiber if pressed while in such heated and softened condition, and that when alkaline solutions are used instead of clear water, such heat and pressure accelerate the softening or dissolving of the gummy matter, and that if sufficient alkalies are used the softening or dissolving of the gummy matter can be effected by boiling at atmospheric pressure.

The nature of our invention consists in preparing the fibers of flax, hemp, and other similar substances for manufacture into short-stapled textile fabrics by subjecting them, while in the vessel in which they have been boiled with water or other liquid, to the action of a piston plunger or equivalent device, so arranged as to press out from the mass the liquid in which it was boiled, together with the gummy and coloring matter, leaving the

fiber in a compact mass, still in the heating vessel.

It also consists in the peculiar manner of washing the fiber while in the vessel in which it has been boiled.

The apparatus in and by which our invention is performed may be of various constructions, but the one herein described we consider the best adapted to the purpose.

A is a curing-vessel of cylindrical form and of suitable size and strength.

B is a bonnet or cover bolted to the top of A.

C is a piston or follower perforated with several holes, *c c c c*.

D is a piston-rod, one end of which is secured to the piston C, and the other end passing through a stuffing-box in the center of B.

E is an aperture in the bottom of A, through which steam from a boiler is admitted to A.

E' is an aperture through which the water or other liquid is drawn from the curing-vessel A.

F is an aperture through which water or other liquid used is admitted into the curing-vessel A.

G is a man-hole through which the material under treatment is admitted into the curing-vessel A, and has fitted to it a manhole-plate, G'.

The operation of the apparatus thus far described is as follows: The material to be treated is placed in the cylinder A, through the man-hole G, and the man-hole plate G' is secured in its place. The piston or follower being at the bottom, water or other liquid used is admitted through the aperture F into the cylinder A until the mass has become saturated. Steam from a boiler is then admitted through the aperture E into the bottom of A, raising the temperature and pressure necessary to dissolve or soften the gummy matter contained in the fibrous material.

It may here be stated that the time required to boil, and the temperature and consequent pressure, is determined by the nature of the material under treatment. When hemp or flax is perfectly ripe, we consider it better to boil it at a temperature of about 275° Fahrenheit, but if the material is not ripe it can be boiled with a weak solution of soda-ash or caustic soda, at atmospheric pressure and 212° temperature.

After the material has been boiled until the gummy and coloring matter is dissolved, the steam and water pipes are closed, and the piston or follower C is raised by any mechanical device applied to the piston-rod D. This causes the liquids contained in the curing-vessel A to pass down through the holes *c c c c* in piston C into the lower part of the curing-vessel A, while the fiber is at the top of the curing-vessel in a solid compact mass. The liquid and gummy matter is then drawn from the curing-vessel A through the aperture E'.

In order to wash the material, the piston C is again lowered and the aperture F is opened, which admits fresh water into the top of the curing-vessel A. The aperture F is then closed and the piston C is again drawn up as before. This operation forces the water through the material under treatment and through the piston into the bottom of the curing-vessel, whence it can be drawn off at the aperture E'. This washing operation can be repeated until the fiber is perfectly clean. It is then taken out of the curing-vessel A, through the man-hole G, when it is ready to dry and pick, card, and spin on short-staple machinery.

We do not claim, broadly, boiling fibrous materials in water or other liquids either with or without pressure, in an open or closed vessel; neither do we claim pressing the gummy and coloring matter out of the fibrous mass by means of a piston-plunger or follower.

What we claim as our invention, and desire to secure by Letters Patent, is—

1. Preparing the fibers of flax, hemp, and other similar substances for Cottonizing, or rendering applicable to short-staple textile fabrics, by subjecting such substances, while in the vessel in which they were boiled or cured with water or other liquids used for softening or dissolving the gummy and coloring matter contained in such substances, to the action of a piston, plunger, or follower, or equivalent device, so arranged as to press the fiber into a solid compact mass in one part of the curing-vessel, at the same time pressing out of the mass all or nearly all the dissolved gummy and coloring matter while such gummy and coloring matter is in a dissolved or softened condition, so that it can be readily drawn off, while the fiber is contained in the curing-vessel, substantially as and for the purposes specified.

2. Washing the cured fiber by the combined action of the piston C, or its equivalent, and of water, in the manner substantially as specified, and for the purposes set forth.

Claremont, New Hampshire, March 2, 1864.
